UNITED STATES PATENT OFFICE

NIKLAS F. EGLER, OF MONESSEN, PENNSYLVANIA

OPEN-HEARTH FURNACE

Application filed April 30, 1931. Serial No. 533,960.

In the operation of open-hearth steel furnaces, fuel and air are admitted to the furnace chamber through a port or ports arranged at one end of the chamber, and the gaseous products of combustion find escape through a port or ports at the opposite end. Periodically the direction of flow is reversed, and the port which had been serving as the intake port becomes the port for the outflow of the products of combustion, while the port which had been the outflow port becomes the intake. The volume of the outgoing products of combustion is vastly greater than that of the incoming fuel and air. This is due both to the chemical changes involved in combustion and to the elevation of temperature incident to combustion. Because of this condition, it long has been a problem, how to fashion and arrange the furnace ports to achieve in largest measure economy of fuel, efficiency of operation, and durability of structure. This invention consists in a port structure designed to achieve good results of the nature indicated.

In the accompanying drawings, Fig. I is a view in horizontal section of the structure of one end of an open-hearth steel furnace in which my present invention is embodied. The plane of section is in Fig. II indicated by the line I—I. Fig. II is a view of the same structure in vertical section, on the plane indicated at II—II, Fig. I. A certain movable member is in the two figures shown in alternate operative positions. Figs. III and IV are views corresponding to Figs. I and II and show the invention in application to a furnace of different character. Fig. V is a view in vertical section, on the plane indicated at V—V, Fig. III. Figs. VI and VII are views corresponding to Figs. I and II and show an alternative arrangement. The furnace of Figs. I, II, VI, and VII is intended to be operated with liquid fuel, such as tar or oil, or with pulverized coal dust borne on a stream of compressed air; the furnace of Figs. III—V is intended to be operated with gaseous fuel.

In the furnace of Figs. I and II the walls of the furnace chamber are indicated at 1, the hearth at 2, and the roof at 3. Ports 4 are

ranged at opposite ends open to the furnace chamber. Into the port 4 extends a nozzle 5, through which fuel is delivered in a jet directed through the port and into the furnace chamber. The particular nature of the fuel is not here important; suffice it here to say that it may be a jet of oil or tar atomized in a stream of compressed air or gas, or it may be a jet of coal dust carried on such a stream. The nozzle 5 is advantageously arranged in the vertical mid-plane of the furnace, and, with the structure of the present invention in view, it is conveniently spaced at an interval above the floor of the port. Rising vertically through the floor of the port on either side of the nozzle 5 and opening into the port 4 are air uptakes 6, 6. Through these uptakes streams of combustion-sustaining air, preheated in usual manner in the regenerator chambers (not shown), enter the port and advance with the fuel to the furnace chamber. The flame springs from the port at one end, and streams through the furnace chamber. The products of combustion pass out through the port at the opposite end of the furnace chamber. Periodically, by the operation of valves (not shown), the direction of flow through the furnace is reversed, the port which had been serving as intake port becomes the outgo port and the port which had been serving for the escape of gases becomes the intake. Such reversal is incident to the use of the regenerator. A regenerator is provided at or in association with each furnace port; the outgoing hot gases sweep through the regenerator and heat to high temperature the checkerwork of the regenerator, and the checkerwork absorbs large stores of heat. When the furnace is reversed, the air on its way to the port (now become the intake port) passes through the regenerator and takes up heat so stored in the checkerwork. By periodic reversal quantities of heat are at intervals stored alternately in each regenerator, and the stored quantities of heat are taken up by the incoming air, rendering it more effective in the rapidity of combustion of the fuel in the furnace chamber.

In the typical open-hearth furnace the same uptakes and port which at one end admit the

components of the combustible mixture to the furnace chamber, serve at the opposite end as the passageways for the escape of the products of combustion; and, as has been said, 5 since the products of combustion are of vastly greater volume than the entering components of the combustible mixture, the designing of an efficient port is an engineering problem of importance. The problem is rendered more 10 difficult by the fact that the outgoing gaseous products of combustion are exceedingly hot and in a condition to act most destructively on the masonry walls of the port and passageways.

15 I provide an auxiliary passageway 7, opening through the floor of the port 4 and arranged in advance of the air uptakes 6—that is to say, nearer to the furnace chamber—and leading to the regenerator. Conveniently, the passageway 7 unites with that from which the uptakes 6 rise, as is best shown in Fig. II. And I provide a cover-plate or slide 8 which, arranged immediately above the floor of the port, is movable in horizontal 20 plane between the two positions illustrated in Figs. I and II. In the position shown in Fig. I the slide 8 overlies the passageway 7 and renders it ineffective; in the position shown in Fig. II the plate is withdrawn and 25 the passageway 7 is open and effective. The proportions preferably are such that the slide 8 when withdrawn from passageway 7 still leaves the uptakes 6 open and unobstructed. The position of slide 8 as seen in Fig. I is 30 its position at the intake end of the furnace; the passageway 7 is then ineffective; regenerated air is entering the port through uptakes 6 and is advancing to the furnace chamber to meet the fuel jetted through nozzle 5. 35 At the outgoing end of the furnace, slide 8 is withdrawn to the position shown in Fig. II, and the products of combustion are streaming out, not through the passageways 6 merely, but through the great augmentation in escape which the passageway 7 affords.

The slide 8 carries abutments 81 of masonry which form and define a constriction or throat in the port through which at the intake end the components of the combustible mixture stream in with increased velocity, 50 to burn with increased intensity.

The slide is advantageously formed, as the drawings show, of a water-cooled marginal frame of metal carrying a low-arched vault of masonry. The circulation pipes 82 for water may be the members by means of which the slide is shifted. The side-walls of the port may be slotted, as indicated, to afford 55 supports upon which slide 8 may rest and move; or (as particularly shown in Fig. V) the port walls may be formed with steps to afford such support. Water-cooled rails 60 83 may be provided as the immediate slide- 65 supporting members; and if the walls be slot-

ted, the slots may be closed by aprons 13 of sheet metal, as indicated in Fig. I. The slide, constructed in the manner described, may readily carry the abutments 81, which themselves also are formed of masonry.

The arrangement shown in Figs. VI and VII, otherwise identical with that of Figs. I and II, is distinguished in that the fuel nozzle 5a is made integral with the slide 8a and moves with it; so that when the slide is withdrawn to uncover at the outgoing end of the furnace the passageway 7, the nozzle 5a is withdrawn from the full sweep of the hot gases streaming through uptakes 6.

The furnace of Figs. III-V is intended for gaseous fuel. In place of a fuel nozzle, an uptake 9 for gas is provided. This uptake opens to the port in the vertical mid-plane of the structure and through a hood 13 delivers its stream into the port and in a direction 80 toward the furnace chamber. As in the other case, the air uptakes 6 are laterally arranged and the components of the combustible mixture meet as they enter the furnace chamber and the flame springs from the port and 85 flows through the chamber. In this case, ordinarily, the gas as well as the air is heated on its approach to the furnace, and to that end a second pair of regenerators is provided, in which the gas is preheated. The 90 outgoing hot products of combustion flow in 95 divided streams through both air and gas regenerators.

In this case the gas uptake 9 at the outlet end of the furnace, as well as the air uptakes 100 6, is advantageously kept open for the outflow of the products of combustion. In place of a single passageway 8 extending across the entire width of the port two such passageways 10 are advantageously provided, 105 symmetrically arranged on opposite sides of the vertical mid-plane of the structure, and two slides 11 are provided, one associated with each of the passageways 10. The slides 11 are severally built and operated in the manner 110 already described. They may severally carry abutments 12 which shall co-operate in the manner already described. Figs. III and V show the slides 11 in the positions they occupy at the intake end of the furnace; Fig. 115 IV shows them in the position which they occupy at the outgoing end. Air and gas stream in through uptakes 6 and 9 and enter the furnace chamber through the gullet formed by abutments 12, 12; the products 120 of combustion escape through passageways 9 and 10. The abutments 12 being then withdrawn, the escape of gases is not hindered by a gullet. Whether the slides 11 when withdrawn effect closure of uptakes 6 is a matter 125 of proportioning of parts. A structure and a procedure such as to effect alternate closure of the uptakes 6 may or may not be resorted to, as circumstances dictate.

The slide 8 (11, 11) is shifted, in co-ordin-

130

nation with the reversal of the furnace, to effect the ends described.

In the operation of the furnace described the products of combustion stream from the 5 furnace chamber through the passageways which open through the floor of the port, with few and slight swirls and eddies and with a minimum of erosion of wall structure.

I claim as my invention:

10 1. In an open-hearth metallurgical furnace of reversing type the combination with a furnace chamber of duplicate ports at opposite ends thereof, an uptake opening through the floor of the port in a portion 15 remote from the furnace chamber, a passageway opening through the floor of the port in a portion adjacent to the furnace chamber, a closure for said passageway movable within the port from a position of closure 20 above said passageway to a position remote therefrom, and a gullet-forming abutment borne by said closure.

25 2. In an open-hearth metallurgical furnace of reversing type the combination with a furnace chamber of duplicate ports at opposite ends thereof, an uptake opening through the floor of the port in a portion remote from the furnace chamber, a passageway opening through the floor of the port in a portion 30 adjacent to the furnace chamber, and a closure for said passageway movable within the port from a position of closure above said passageway to a position remote therefrom, the interval at which the openings through 35 the floor of the port to the said uptake and to the said passageway stand apart being as great as the width of said closure.

3. In an open-hearth metallurgical furnace 40 of reversing type the combination with a furnace chamber of duplicate ports at opposite ends thereof, an uptake opening through the floor of the port in a position remote from the furnace chamber, a passage opening 45 through the floor of the port in a position adjacent to the furnace chamber, a slide movable within the port from a position of closure above said passage to a position remote therefrom, and a fuel nozzle mounted integrally with and movable in unison with said 50 slide from active to inactive position.

4. In an open-hearth metallurgical furnace of reversing type the combination with the furnace chamber of duplicate ports at opposite ends thereof, an uptake passage opening through the floor of the port, a slide movable in the direction of the length of the furnace upon the floor of said port, said slide bearing a gullet-forming abutment standing 60 in the assembly athwart the port, said slide in its advanced position covering said passageway and closing access of the components of the combustible mixture to the furnace chamber except through such gullet, and 65 the said slide when in withdrawn position

leaving open escape for the products of combustion from the furnace through such passageway without constriction in such gullet.

In testimony whereof I have hereunto set 70 my hand.
